WAX PLATE STAMPING MACHINE

Jacob Stanley Haas, Buffalo, N. Y.

Application November 3, 1930. Serial No. 493,067

6 Claims. (Cl. 101—4)

This invention relates to printing and more particularly to a machine for pressing type or type plates into the surface of a wax coated copper plate or other similar soft-surfaced plate 5 upon which, subsequently, a final printing plate is to be cast.

The objects of the invention are: (1) to permit of so stamping a wax plate with one or more lines of type at a time and in such manner that a very 10 high relief may be obtained upon the same without the need of "building up" said plate subsequently to the stamping operation proper, as is the customary present practice; (2) to permit of obtaining such a high relief without, at the same 15 time, causing the sharp corners in the wax impression to be jagged or roughened; (3) to permit of stamping the wax plate a number of times in correct register, and each time obtaining a higher relief until inspection of the stamped 20 wax plate shows the same to have a perfect impression; (4) to definitely limit the extent of movement of the type into the surface of the wax plate; (5) to permit the operator to very 25 accurately gauge the pressure exerted by the type upon said wax plate without requiring him to use his hands or arms for the purpose; (6) to stamp the type into the wax plate with an even pressure and with a perfectly translational 30 movement; (7) to enable the wax plate to be accurately indexed at a number of 90° positions so as to enable a column or row of type to be 35 printed either vertically or horizontally on the wax plate; and, (8) to provide a set of type boxes for holding the type which permits of rigidly 40 and accurately setting up the requisite type, spacers, etc. therein. Numerous other objects of the invention and practical solutions therefor are disclosed in detail in the herein patent specification wherein:—

40 In the accompanying drawings:—

Figure 1 is a diminutive front elevation of the stamping machine with one part in section and taken on line 1—1, Fig. 4. Figure 2 is a diminutive diagrammatic face view of a typical printed 45 sheet in the production of which the present invention constitutes an intermediate step. Figure 3 is a diminutive side elevation of the stamping machine. Figure 4 is a diminutive plan thereof. Figure 5 is a fragmentary, vertical, longitudinal section through the stamping table and associated parts taken on line 5—5, Fig. 4. Figure 6 is a face view of the large size 50 of type box showing a typical set of type and spacers in place. Figures 7 and 8 are vertical, transverse sections thereof taken on correspond-

ingly numbered lines of Fig. 6. Figure 9 is a front view of a medium size of type box. Figure 10 is a vertical, transverse section thereof taken on line 10—10, Fig. 11. Figure 11 is a face view thereof. Figure 12 is a face view of the 60 small size of type box. Figure 13 is a front view thereof. Figure 14 is a vertical, transverse section thereof taken on line 14—14, Fig. 12. Figure 15 is a face view of the tiny size of type box. Figure 16 is a front elevation thereof taken on 65 line 16—16, Fig. 17. Figure 17 is a vertical, transverse section thereof taken on line 17—17, Fig. 15.

In the following description, similar characters of reference indicate like parts in the several figures of the drawings.

My invention may be embodied in various forms and in stamping machines of different constructions and the present application is to be regarded merely as one organization which satisfactorily carries out the invention in practice. As here shown the same is constructed as follows:

The main frame of the machine comprises a pair of vertical, longitudinal side walls or frame panels 20 and 21 which are provided with the feet 80 22 and 23 respectively that rest on the floor. Said frame panels are integrally or otherwise connected at their upper ends by transverse tie bars 24. Extending vertical and longitudinally above said frame panels 20 and 21 and integrally or otherwise secured thereto are carriage-ways or V slides 25 and 26 which are suitably braced to the rest of the main frame by abutments 27.

Slidably arranged upon said V slides 25 and 26 90 is a carriage 28 which is constrained to move accurately in a horizontal and longitudinal direction by the reason of the V shaped grooves 30 and 31 which are formed in its lower face and which slidably engage with the V slides 25 and 26 of the machine frame. Formed upon the lower face of said carriage is a longitudinal gear rack 32 which is engaged by a spur gear wheel 33. The latter is secured to the central part of a horizontal, transverse shift shaft 34, the outer 100 ends of which are suitably journaled in bearing heads 35 and 36, the latter being suitably secured to the outer faces of the frame panels 20 and 21 by cap screws 37 or otherwise. This shift shaft 34 is adapted to be manually rotated (so as to longitudinally shift the carriage 28) by means of a hand wheel 38 which is pinned to the outboard end of said shift shaft 34. Endwise movement of said shift shaft is prevented in one 105 direction by the hub of said hand wheel 38 and 110

in the other direction by a retaining collar 39 which is detachably secured to the other end of said shift shaft.

5 Rotatably mounted upon the central upper face of the carriage 28 is a table 40 which rotates about a central vertical stud or pin 41 (see Fig. 5), whose lower end is tapered and is received within a vertical tapered hole 42 formed in the upper central part of the carriage 28. This table is adapted to be accurately indexed in any one of 10 four positions which are 90° from each other. This is accomplished by providing a horizontal, longitudinal index pin 43 which is screw threaded into the front central part of the carriage 28 so that, when screwed inwardly, it engages snugly 15 with any one of four index holes 44 radially formed in the lower annular flange 45 of the table. The handle 46 of said index pin projects laterally from one side thereof so that it normally tends to hang downwardly and thus to prevent vibration of the whole machine (or of the floor upon which it is placed) from gradually causing 20 said index pin to unscrew and to allow the table to be thrown out of index.

25 A wax coated copper plate 46 (hereinafter to be referred to as a wax plate) is adapted to be laid on the upper flat horizontal surface of said table 40, and is held firmly in place by a pair of detachable cleats 47 which are adapted to be pressed toward the upper face of the table 40 by means of suitable clamping cap screws 48. Inasmuch as the size of this plate may vary considerably in both breadth and length for different printing jobs, two radial rows of tapped holes 30 50 are suitably formed at 90° to each other in said table 40 so that the pair of clamping cap screws 48 with their companion cleats 47 may be screwed into any desired pair of holes in either of said rows. More than two pairs of clamps may, of 35 course, be used on very large work.

40 Threaded vertically in each of the bearing heads 35 and 36 (see Fig. 1) is an upper or type-carrier-adjusting bushing 51 and a lower or spring-adjusting bushing 52. Each set of said bushings is in vertically axial alignment, and within the bores of each set is vertically and slidably arranged a guide head 53, to which is secured a collar 54 intermediately of said bushings. This collar is adapted to bear against the lower 45 end of its companion upper bushing 51 and to thereby limit the upward movement of its companion guide head 53 relatively to said companion upper bushing. Interposed between the lower face of each collar 54 and the upper end 50 of its companion lower bushing 52 is a compression spring 55 which encircles the intermediate part of its companion guide head and operates to resiliently force the same to the upper limit of its movement. The tension of said spring 55 55 may be adjusted as desired by screwing the lower bushing 52 up or down to the desired position and then locking in position by a set screw 56. The upper bushing is locked in its proper position by a similar set screw 57.

60 The two guide heads 53 are adapted to be depressed against the resistance of said springs 55 by means of a pedal or foot treadle 58 whose hub is secured to the central part of a horizontal transverse rock shaft 60 and extends forwardly 65 and approximately horizontally therefrom. The outer portions of said rock shaft are suitably journaled in the main frame of the machine and have secured thereto a pair of arms 61, which extend forwardly from said rock shaft and are 70 pivotally connected at their forward ends to the 75

lower ends of companion depression links 62. Each of these links comprises a pair of end yokes 63, an intermediate, threaded tie bar 64 and lock nuts 65, this arrangement permitting any desired adjustment in the lengths of said depression links 62 so as to have the foot treadle 58 at any desired height above the floor upon which the machine rests. The upward movement of said foot treadle is limited (in addition to the collar 54) by the provision of a horizontal, transverse stop rod 66 whose opposite ends are secured in the machine frame. A rubber tube or other suitable resilient buffer 67 is slipped over said stop rod 66 at its intermediate point so as to cause the upward stopping of the foot treadle 58 to be rendered noiseless. This construction enables all of the moving parts to be quietly but positively brought to rest even after the various pivotal connections have become badly worn as a result of prolonged use.

90 Arranged horizontally and transversely at the uppermost part of the machine is a type carrier 68 which is provided at opposite ends with trunnions 70 which are journaled in the upper ends of the guide heads 53. The type carrier is adapted to be rotated into either of two positions which are 180° from each other. This turning is effected manually through the instrumentality of either one of a pair of handles 71 which are secured to opposite ends of said type carrier and 95 extend transversely and outwardly therefrom. The exact position of this type carrier in its two 100 180° positions is rendered adjustable by the provision of two pairs of adjusting screws 72 and 73 which are adapted to limit the rotary movement 105 of the type carrier by coming in contact with the shanks of the handles 71 and are locked in properly adjusted position by lock nuts 74. It should be noted that, except for these handles, 110 the type carrier and everything else which rotates with it is laterally, statically balanced in each of its 180° positions. The fact that these handles 71 extend laterally and horizontally out from said type carrier in each of its said 180° positions, creates an overbalanced condition which 115 causes said handles to be firmly held in contact with the heads of the adjusting screws 72 or 73, as the case may be, and thus to firmly hold the type carrier in each of its 180° positions.

120 The one horizontal longitudinal face of the type carrier 68 is provided longitudinally of its axis with a dove-tailed slide 75 along which may be adjustably moved any desired one of a number of type boxes, for instance "small" type box 76c. Within said type box is clamped any desired 125 sort or arrangement of type 77 in a manner to be hereinafter described in detail. The box itself is clamped in any desired position upon the slide 75 by a clamping screw 94. In Figs. 1, 3 and 4 this small size of type box 76c is shown with its 130 type facing upwards. This is the most convenient position for placing said box upon or removing the same from said slide 75 and is also the most 135 convenient position for inserting, inspecting or re-arranging the type and for lubricating the same. The usual lubricant used to moisten the type is soapy water and in this position said lubricating water may also be most readily applied, if desired, to the upper face of the wax plate 46.

145

Operation

To bring said type box into operative position one of the handles 71 is grasped by the operator and swung up and around and then down, until both of said handles rest upon the heads of their 150

companion adjusting screws 72. This causes the type 77 in said type box to face downwardly. If the type box is not absolutely parallel to the top face of the table 40, it may be suitably adjusted by manipulating said adjustment screws 72 and then locking the same in place by means of their companion lock nuts 74. If an adjustment transversely of the table is also necessary, this may be accomplished by suitably screwing in or out one or other of the threaded tie bars 64 of the treadle mechanism and then locking in place by the lock nuts 65.

The operator then brings the type into correct longitudinal register by moving the hand wheel 38 in the one or other direction, thereby shifting the carriage 28, table 40 and wax plate 46 to the desired longitudinal position relatively to said type box 76c and type 77. Proper transverse register is obtained by loosening the clamp screw 94 (to be hereinafter described) and shifting the type box (76c for instance) along the dovetailed slide 75 of the type carrier and then clamping in position by tightening said clamp screw 94. The operator now depresses the foot treadle 58 until the type is close to the wax plate at which time he can very accurately check the type position. If this is correct (and correction is advantageously made while the type is thus close to the wax plate) he continues to depress said foot treadle with a relatively light pressure until he has obtained a light impression of the type 77 upon the upper surface of the wax plate 46. He then releases his pressure upon said foot treadle 58 and this causes the type box 76c with its type carrier 68 to be returned to its elevated position under the influence of the two compression springs 55. The impression in the wax surface of the wax plate is then scrutinized by the operator and, if defects are shown, the type box 76c may be flipped back to the position shown in Figs. 1, 3 and 4 as, in this position, the type 77 within said type box may be conveniently rearranged or altered to correct whatever errors were disclosed by the light impression on the waxed plate. Ordinarily in such a case the spoiled wax plate 46 is repaired with a hot poker while remaining upon the table 40. If, however, the impression is correct as to both type and register, the operator merely scrapes off the "burrs" and again moistens the type 77 and/or wax plate 46 and throws the type box down and again depresses the foot treadle 58, this time causing the type to be pressed further and usually clear through the wax of the said wax plate and against the copper plate 46a which forms a backing for said wax plate. With the present invention, a very high relief may be obtained directly on the machine and without any necessity of "building up" the wax plate by reason of the fact that the type carrier may be jiggled up and down as much as desired or otherwise caused to make a succession of ever deeper type stampings, the type and/or wax plate being scraped free of "burrs" and lubricated prior to each of the usually two individual stamping operations. The jiggling up and down referred to is only necessary where very fine type is used or a very high quality of work desired and this operation may be performed without anything more than the usual "burring" and lubricating operations. Such a succession of stampings is rendered possible by the fact that each impression will be in exactly the same register as all other impressions. The value of this feature of the machine will be more apparent if it be contrasted with the present method of stamping wax plates in which each

wax plate is necessarily covered by only a very thin coating of wax and hence necessitates a subsequent complicated "building up" process to obtain a reasonably high "relief."

The operator with the present machine can successively stamp a wax plate in as many successive steps and as many "jiggles" as the character of the work warrants, the applied pressure being very delicately under his control and yet capable of very heavy pressures by reason of the fact that the pressure is obtained directly by his own depression of the foot treadle. At the same time and even though this pressure may be very delicately under the operator's control, nevertheless the operation is such as to leave the operator's hands and arms entirely free to busy themselves with the very important work connected with the manipulation of the successive type boxes and the wax plate, particularly the accurate gauging of the type as it comes into proximity with the wax plate.

It is, of course, desirable that the type be pushed just clear through the wax of the wax plate and no more. This amount is adjusted by moving up or down the two, type-carrier, adjusting bushings 51, the upper ends of which come into contact with shoulders 80 formed at the upper part of the guide heads 53 and operate to limit the downward movement of the type carrier 68 and the type box 76c relatively to the table 40 and the wax plate 46. It is desirable that the quantum of up and down movement of the type carrier 68 be of definite amount irrespective of the thickness of the wax coating or of the copper plate 46a of the wax plate. The present construction obtains such a result in that, as the upper or type-carrier adjusting bushings 51 are adjustably moved up or down to limit the downward position of the type carrier 68, they at the same time and to the same extent alter the upper limit of motion of said type carrier by reason of the fact that the latter is pushed upwardly by its springs 55 until the top face of the collar 54 comes in contact with the lower end of said upper bushing 51. In this way the type 77 in box 76c properly clears the upper face of the wax plate 46 irrespective of the thickness of the latter (assuming that the relief to be obtained is constant as is ordinarily the case).

Type setting arrangements

The indexing of the table 40 to any one of four positions which are 90° from each other is a feature which permits of very fast production work in type set ups. One of the chief reasons for this is that table indexing is a feature which has not heretofore been used. To obtain a realization of the significance of this feature attention is directed to Fig. 2. This illustrates diagrammatically a printed sheet of paper such, for example, as a shop record form 81 upon which is printed a heading 82a; a full lined vertical column 82b; a triple line of type 83; a single line of type 84; and a spaced line of type 85. The division lines between these columns and between them and the heading 82a are cut out later with a V chisel and are here disregarded for purposes of simplicity. Such a record form 81 is, of course, illustrative only, it being understood that all sorts of type setting and type plate arrangements which arise in practice are taken care of by the equipment here illustrated. In the present example the heading 82a and long vertical column 82b would be set up in the large sized type box 76a shown in Figs. 6-8;—the triple line of type 150

83a in the medium sized type box 76b shown in Figs. 9-11;—the single line of type 84 in the small sized type box 76c, Figs. 12-14;—and the spaced line of type 85 in the tiny sized type box 76d, Figs. 15-17. In this example it is assumed that the large sized box 76a when printing the heading 82a, is disposed “horizontally” of the wax plate 46 and that, when printing the long vertical column 82b, is disposed “vertically” of said wax plate 46. All the other type boxes are disposed “horizontally” of said wax plate in the particular illustration given, but may be arranged to suit whatever may happen to be the particular requirements. In other words, the arrangement 15 of this improved stamping machine is such that the long direction of each type box may be positioned in the longest direction of the space to be printed. It is to be understood that the present machine does not do the actual printing, nor does it even produce printing plates, but merely enables the rapid production of the wax plates from which printing plates are subsequently made by the electrotyping process.

The large type box 76a (Figs. 6-8) for printing the full lined column 82b of Fig. 2 (and also the heading 82a) comprises longitudinal side walls 79 and 791 and end transverse walls 86 secured thereto by rivets 87 or otherwise. The bottom 83 of said type box may, as shown, be formed integrally with said side walls 79 and 791 and has formed on its outer (lower) side a longitudinal dovetailed slot 90 which is adapted to slidably receive the dove-tailed slide 75 of the type carrier 68. A take-up section 91 at one side of said slot (see Fig. 7) is adapted to be moved transversely inwardly by a take-up screw 92 to compensate for wear, said take-up section being locked in adjusted position by a suitable, locking, countersunk cap screw 93. The whole type box 40 76a is clamped in any desired position along the dove-tailed slide 75 of the type carrier 68 by means of a clamp screw 94 (see Fig. 8) which carries a thrust block 95 at its inner end and is adapted to force said block against the adjacent face of the type carrier and to thus clamp the type box firmly thereto. This form and size 45 of type box is ordinarily used where it is desirable to have the lines of type lie transversely of the length of said box as shown in Fig. 6, (but may also be used for long horizontal lines as for instance heading 82a). After the type 77, spacers 96 and filter pieces 97 have all been arranged in proper position, all of the same are clamped lengthwise by a pair of end clamping screws 98, 50 which are threaded through one of the end walls 86 of the type box and bear with their inner ends against an end pressure plate 99 arranged at the adjacent extreme end of the block of the type and spacers. Side clamping is desirable to withstand the side pressure imposed upon the type as the latter enters the wax, said side pressure being caused by the unsymmetrical shape 55 of the type letters. This side clamping (though not in all cases necessary) may be effected by three side clamping screws 100 which are threaded through the side wall 79 of the type box and bear with their inner ends against a heavy side pressure plate 101 which lies against the sides 60 of the block of type and spacers. This side pressure plate is suitably slotted at 102 so as at all 65 times to properly clear the inwardly projecting ends of the end clamping screws 98, and is preferably so slotted at both ends, as shown, so as to be reversible.

70 Figs. 9-11 illustrate the medium size of type

box 76b that is particularly adapted for use with those set-ups in which a plurality of lines of type or a row of type impressions, one of which has a plurality of lines of type, are to be disposed “horizontally” of the wax plate 46. Such a condition arises for instance in printing the triple line of type 83a (and also the single line of type 83b in the same row) of the form card 81 shown in Fig. 2. In this case, only side clamping of the type and spacers is necessary, this being preferably accomplished by a pair of side clamping screws 103 which are threaded through bushings 104 in the side walls 79b of the type box and are provided with heads 105 at their inner ends which are countersunk into and bear against the adjacent face of the side pressure plate 101b. When these clamping screws 103 are retracted to loosen the block of type and spacers, said side pressure plate 101b is constrained to likewise move outwardly by the provision of confining straps 106 which bear against the outer faces of the heads 105 of the clamping screws 103 and are secured to the adjacent outer face of said side pressure plate by machine screws 107 or otherwise. In constructing these type boxes or 100 in disassembling the same it is desirable to render the screws 107 accessible and this is accomplished by the provision of screw driver holes 109 which permit a screw driver to be passed through the companion side walls 79b and to 105 engage with the screw slotted heads of said screws 107.

Where the type is to be centered (as in this case) it is desirable to be able to build up the same against an adjustable abutment plate 108 110 which lies against the inner face of the side wall 791b of the type box 76b and is provided with a square faced guide rib 109 which is slidably received within a longitudinal slot 110 formed in said side wall 791b. This adjustable abutment 115 plate is held in any desired longitudinal position by a clamping screw 111 which is threaded centrally through said guide rib 109 and into the main body of said abutment plate and bears with its head against the outer face of said side wall 120 791b of the type box. When starting to set the first line of type 770, this abutment plate 108 is placed in the position it should probably have ultimately and the individual slugs of type then laid against it. When this operation has been 125 completed and the exact length of the entire line of type 770 definitely fixed, the clamping screw 111 may then, if necessary, be loosened and the whole line of type 770, together with the abutment plate 108, pushed longitudinally in the one or 130 other direction until the entire line of type 770 has been centralized. The clamping screw 111 is then tightened and the type setting process continued by using this first centralized line of type 770 as a guide. This first line of type may be 135 built up from either the right or the left side of the type box 76b, a second slot 110b being provided at the right side of the type box and symmetrically disposed with respect to the left slot 110 just described. This enables the operator to 140 remove the abutment plate 108 from the left slot 110 and to place it in the right slot 110b and to then pile up his line of type slugs, starting at the right end of the line.

145 Figures 12-14 illustrate a small sized type box which may be advantageously used in setting up, for instance, the single line of type 84 shown in Fig. 2. This construction is analogous to the medium sized type box of Figs. 9-11, except that only one slot 110c is employed which runs clear 150

across the face of one of the side walls 791c of said type box. Also only a single side clamping screw 103c is provided.

The tiny sized type box shown in Figs. 15-17 is adapted, for instance, to the stamping of a wax plate upon which impressions 85 are to be made in such spaced relationship as to permit the use of a plurality of boxes on the type carrier bar at the same time.

10 I claim as my invention:

1. A wax plate stamping machine comprising a frame; a table arranged on said frame; means for clamping a wax plate upon said table; a type carrier also arranged on said frame and movable toward and from said table; a type box adjustably and slidably arranged on said type carrier and adapted to have type arranged therein.

2. A wax plate stamping machine comprising a frame; a table rotatably arranged on said frame and adapted to hold a wax plate, and a type carrier also arranged on said frame and movable toward and from said table and adapted to have type secured thereto.

3. A wax plate stamping machine comprising a frame; a table rotatably arranged on said frame and adapted to hold a wax plate, a type carrier also arranged on said frame and movable toward and from said table and adapted to have type secured thereto, and means for indexing said table in a plurality of definite positions.

4. A wax plate stamping machine comprising a frame; a table rotatably arranged on said frame and adapted to hold a wax plate, a type carrier also arranged on said frame and movable toward and from said table and adapted to have type secured thereto, and means for indexing said table at positions which are ninety degrees relatively to each other.

5. A wax plate stamping machine comprising a frame; a table arranged thereon and adapted to hold a wax plate; a guide head slidably arranged on said frame perpendicularly to said table; means for actuating said guide head, a type carrier pivotally mounted on said guide head to swing through a half circle and adapted to have type secured thereto, and means for adjusting said type carrier relatively to said guiding head.

6. A wax plate stamping machine comprising a frame; a table arranged on said frame and adapted to hold a waxed plate; a type carrier perpendicularly movable relatively to said table and adapted to have type secured thereto; means for adjusting the limit of approach of said type carrier to said table; and means for causing a constant total amount of reciprocation of said type carrier irrespective of the adjustment of its limit of approach to said table.
